UNITED STATES PATENT OFFICE.

EMIL JENDIS, OF CHICAGO, ILLINOIS.

SHOWER-BATH.

SPECIFICATION forming part of Letters Patent No. 596,115, dated December 28, 1897.

Application filed April 21, 1897. Serial No. 633,077. (No model.)

To all whom it may concern:

Be it known that I, EMIL JENDIS, a citizen of the United States, residing at Chicago, in the county of Cook and State of Illinois, have 5 invented certain new and useful Improvements in Shower-Baths, which are fully set forth in the following specification, reference being had to the accompanying drawings, forming a part thereof, and in which—

10 Figure 1 shows my said device in elevation as seen from one of the side openings with some of the pipes broken away and case, floor, and walls in section and valve and connections in side view. Fig. 2 shows the valve and 15 its connections from the under side. Fig. 3 shows the sprinkler-pipes as seen from the plane 3 3, cutting Fig. 1, as shown. Portions only of the pipes are shown. Fig. 4 shows the sprinkler-pipes as seen from the cutting- 20 plane 4 4 of Fig. 1, together with the feed-pipes c and the pan or case in section with its discharge-pipe. Fig. 5 shows a sectional view of the shell of the valve or valve-casing, its 25 supply-pipe, dial, operating-lever, and its bracket and part of the shaft, and the valve and the remainder of its shaft and the valve- 30 openings in perspective. Fig. 6 shows a section of the valve and its casing on the plane 6 6 of Fig. 5. Fig. 7 shows a sectional view 35 of the operating-lever, the toothed wheel operating with the lever, and spring-bolt stops, taken on a cutting-plane 7 7 of Fig. 5. Fig. 8 shows an end view of the wall-bracket h.

Like letters of reference denote like parts.

35 The object of my invention is to produce a shower-bath wherein showers or sprays are produced from vertical pipes from different directions and also different regulable heights, whereby the action of the shower or showers 40 may be made specially local to the person or in the same construction adapted to persons of different heights and, again, so arranged that the shower may come from the front or the rear, or from both directions at the same 45 time, or from the four corners alone, or from the top alone, or from all said places simultaneously by means of a single valve provided with a series of special openings connected with discharge-pipes operated, adjusted, and 50 indexed by a single operating-lever and other mechanism connected with said parts, constructed substantially as follows, namely:

Between walls a, preferably portable, forming front and rear sides of a small chamber, are erected a series of vertical sprinkling-pipes which stand in a box b. Said pipes are provided with small holes f^x from the bottom up to the necessary height for a tall person, and on each jet-pipe is placed a sleeve f^y, which holds by friction, for the purpose of cutting off such parts of the shower as are not wanted, as at the top or from the middle or lower part of the person and for short persons and children. Within the front one of said walls are placed the corner-pipes f^z, and about equally spaced between said corner-pipes are two pipes f⁶, and between said latter pipes are two supply-pipes c, each provided with a cock j, above which said pipes unite into one which is coupled to the center of one end of a cylindrical shell d, provided with an internal cylindrical shell with a series of ports e e' e² e³ e⁴ e⁵, which discharge through several sets of openings e⁷ f⁴ in the bottom of the shell d into pipes which feed the sprinkler or jet pipes, of which certain special sprinkling-pipes are connected with certain openings in the valve e.

In my preferred construction or arrangement the front corner-pipes f^z and rear corner-pipes f⁵ are connected through the pipes f' with the twin valve-openings e', which extend half-way around the shell. The intermediate pipes f⁶ of the front-wall set are connected through the connecting-pipes f² with the valve-openings e², and the intermediate pipes f⁷ of the rear wall are connected through the pipes f³ with the valve-port e³. A part of the pipes f³ are shown in the sectional view Fig. 6, where said opening f³ is shown in full length. The beginning of each of the slotted openings e' e² e³ is on the same straight line parallel with the axis of the cylinder and each placed over its pipe-openings e⁷, as shown in Fig. 6. The round hole e⁵ fits over its discharge opening f⁴ when said three slotted ports are fully open and placed as shown in Figs. 5 and 6. The round hole e¹ is placed so as to let the valve discharge through the pipe f⁴, with its rose-sprinkler e⁶, when the next full stop motion is made of the valve e from the position in which it is now shown in Figs. 5 and 6. In its present position all the valve-ports discharge through all the shell-ports e⁷.

- In Fig. 6 the witness-marks to the reference-letters indicate the farther part of the port, or that end which leads when the valve is revolved in the direction indicated by the arrow.
- 5 The valve-shell has a cap d' , which covers the end through which the valve e is inserted into its shell, and through the center of said cap and its stuffing-box passes the valve-stem e^0 , which is extended into a wall-bracket h , on which there is a projecting part to hold a spring-bolt g^2 . (Shown in Figs. 5 and 7 and in front end view in Fig. 8.) The end of the valve-stem or shaft is carried in the round hole shown in Fig. 8, and on the said shaft, next to the bracket, is a wheel g^4 , with notches g^5 , keyed to the shaft, and next to said wheel is a circular shell or cap surrounding said wheel and carrying a spring-actuated bolt g' , which is also adapted to fit into said notches g^5 . There is a long lever-handle g to said shell, which is loose on the shaft e^0 , and in front of the hub of said cap is a dial i , with the first seven Arabic numerals of which that number which is on the lowest part of the dial indicates the position of the valve. As indicated in Fig. 3, the port e^3 is open. From said dial may therefore be known what parts of the valve are open, a fact always necessary to know if one wishes to get a desired stream or streams of water. In the position in which the valve is shown in the drawings all the streams are fully open. One full motion of the lever g will now shut off all the streams and the next full stop will open the port e^4 into f^4 only, and another full motion of said lever will shut off said flow, and the next motion after said stop will open the ports e' , which will flow water through the pipes f' into all the corner-pipes f^5 . Another motion of the lever will open the port e^2 and flow the pipes $f^2 f^6$, and another full motion of the lever will open the port e^3 and flow the pipes $f^3 f^7$, all the preceding ports lettered e being also open, after which another operation of the valve-lever g will also open the port e^5 through f^4 and its rose-sprinkler e^6 , which is again the condition of the valve e , as shown in the drawings, as the bolt g^2 is placed vertically over the shaft e^0 , and since the lever g moves in equal angles to each side of the perpendicular an intermediate set of notches g^5 is necessary for the bolt g^2 , of which the office is to prevent any retrograde movement of the valve e and also to cause the valve to take its proper place for each lever motion, said bolts $g' g^2$ and their notches being so shaped as to yield automatically to the rotation of the wheel when in the right direction, but to hold it against any reverse motion.
- 6 There is a thin partition f between the two double sets of pipe-openings in the shell d . Therefore, as shown, jets may be thrown from the four corner-pipes, to which may be

added the front intermediate, then the rear intermediate, and finally the overhead flow, which are all cut off at one motion of the lever, after which another motion of the lever again reinstates said last or overhead flow alone, which may again be stopped, after which the corner-jets may be started and operated alone and a new revolution of the valve has begun which when completed will produce the above-described effects. A curtain k closes the opposite wall-less openings or sides and keeps the falling water within the basin. As the feed-pipes, hot and cold, unite above the cocks j into one entrance-pipe c into the interior of the valve e , the water becomes thoroughly tempered to the desired degree, which is easily and perfectly regulable by means of said cocks.

All the sprinkling-tubes direct their jets toward the axial center of the chamber, and the overhead rose-jet is axially on the axis of the chamber. Waste-pipes d^2 discharge the water from diagonally opposite corners of the pan.

What I claim is—

1. The combination with a series of vertical jet-pipes, and supply-pipes, united into one valve-supplying pipe, of a valve-casing with cylindrical valve, and a series of transverse valve-ports of graded lengths whereof one end of each slotted port is in a line parallel with the valve-axis, and shell-openings for said ports, a valve-stem with a notched operating-wheel, and operating-lever with spring-bolt to said wheel, substantially as specified.

2. The combination with a series of vertical jet-pipes and supply-pipes, united into one valve-supplying pipe, of a valve-casing and cylindrical valve therein, with round and slot-formed ports of graded lengths having one end on a line parallel with the valve-axis, and double shell-openings connecting to said jet-pipes, and mechanism to rotate said valve, substantially as specified.

3. The combination with a valve-shell with one entrance and a series of exit-ports, of a hollow cylindrical, continuously-in-one-direction-revolving multiported valve, said ports cut transverse to cylinder and of varying lengths but starting from a straight line parallel to the valve-axis, substantially as specified.

4. The combination with a valve-shell with entrance and exit ports, of a hollow cylindrical continuously-in-one-direction-revolving multiported valve, said ports of varying lengths and positions, an oscillating operating-lever, a notched wheel to the valve-stem and a spring-actuated bolt, substantially as specified.

EMIL JENDIS.
